UNITED STATES PATENT OFFICE.

JAMES E. GIBSON, OF WINONA, MISSISSIPPI, ASSIGNOR OF TWO-THIRDS TO
JAMES C. PURNELL AND A. B. WADDINGTON, BOTH OF SAME PLACE.

NUT-LOCK.

SPECIFICATION forming part of Letters Patent No. 290,638, dated December 18, 1883.

Application filed November 8, 1883. (No model.)

To all whom it may concern:

Be it known that I, JAMES E. GIBSON, a citizen of the United States, residing at Winona, in the county of Montgomery and State 5 of Mississippi, have invented certain new and useful Improvements in Nut-Locks, of which the following is a specification, reference being had therein to the accompanying drawings.

10 My invention relates to nut-locks, and has for its object the securing of nuts upon bolts. This I accomplish by means of a spring-pawl secured within one side of the nut, the inner end of the pawl being made to catch into longitudinal grooves in the bolt, as will be hereinafter more fully described.

To enable those skilled in the art to make and use my invention, I will proceed to describe its construction and operation.

20 In the annexed drawings, making part of this specification, Figure 1 represents a plan view, and Fig. 2 a cross-section, of the nut, taken on the line *x*.

In the figures, A represents a bolt of ordinary construction, except that its threaded portion is provided with one or more grooves made longitudinally of it.

B represents the nut formed to pass over this bolt. The peculiarity of this nut is that 30 it has a rectangular opening formed in one side, or rather edge, of it, a portion of said opening extending into the threads of the bolt.

C represents a pawl made in bell-crank shape, which is inserted in the opening *e* of 35 the nut, and pivoted thereto at the intersection of its two arms. (Seen at *x*.) Beneath one

arm of the pawl, and resting upon a ledge of the opening *e*, and within the nut, is a spring, *d*. This spring may be in spiral or other suitable form. The other arm of the pawl reaches 40 down through the opening to the bolt, and engages normally with the grooves in the bolt. The end of the arm under which the spring lies extends just above the surface of the nut, so that when it is desirable to disengage the 45 lower or inner end from the grooves of the bolt all that is necessary to do is to press the thumb upon and bear it down. The width and length of the opening so nearly correspond with those of the pawl that nothing, as 50 a general thing, can reach the pawl to prevent its successful operation.

I am aware that grooved bolts and pawls connected to nuts are not new; hence I disclaim such general idea as my invention; but, 55

Having thus fully described my invention, what I claim as new, and desire to secure by Letters Patent, is—

In combination with a longitudinally-grooved bolt, a nut having a rectangular central opening formed in one edge, a bell-crank pawl fitted therein, and a spiral spring resting upon a ledge in the opening and bearing against the outer arm of the pawl, substantially as and for the purpose set forth. 60 65

In testimony whereof I affix my signature in presence of two witnesses.

JAMES E. GIBSON.
